UNITED STATES PATENT OFFICE.

ERNEST E. HEINZ, OF DETROIT, MICHIGAN, ASSIGNOR TO TERNSTEDT MANUFACTURING COMPANY, OF DETROIT, MICHIGAN, A CORPORATION OF MICHIGAN.

REMOTE CONTROL LATCH.

Application filed April 10, 1925. Serial No. 22,016.

This invention relates to a remote control latch for automobile doors which permits the location of the actuator unit close by the place where the occupant sits so that he need not lean forward in unlatching and opening the door.

The object of this invention is to provide a remote control in which are provided means for translating and reversing the motion generated in the actuator unit so as to properly retract the latch bolt.

In the drawings:

Fig. 1 is a perspective view of the inside of an automobile showing in dotted lines my remote control for the door lock.

Fig. 2 is an elevational view of the latch remotely located from the actuator and the connections therebetween.

Fig. 3 is an edge elevation looking upwardly at the device, as shown in Fig. 2.

Fig. 4 is a section on the line 4—4 of Fig. 2.

Fig. 5 is a detailed perspective of the bell crank in the actuator unit.

The automobile door *a* is provided with the usual latch board on which is secured the latching unit *b* and the actuator unit *c*. The latch is provided with a sliding bolt *d* provided with the lug *e* on the one end, to which may be attached the draft member *f*. The actuator unit comprises a plate *g* on which is journaled a vertical rotary spindle *h*, and the lever *i* is pivotally supported on said actuator plate, and is provided with the lug *j* to which the other end of the draft member *f* may be attached. I have here shown the connection between the draft member and the actuator and latching units as a quickly detachable lost motion connection which enables the manufacturer of the latch to ship the latch, draft member and actuator unit separately, and which may be assembled to the automobile by the body manufacturer.

A vertical rotary spindle is provided with the crank shaft portion *k* and the lever is provided with the turned up ear *m* which is adapted to be engaged by the crank shaft portion of the vertical rotary spindle whereby the movement of said spindle imparts a movement of the lever about its pivot. The draft member *f* is connected to the other end of the lever, as shown in Fig. 2, the movement of the spindle to the right causing the lever to rotate in a counterclockwise

direction, thus translating the rotary motion of the actuator unit into a reverse rectilinear movement of the draft member and sliding bolt which is secured thereto.

The purpose of having a reversibly as well as a translating means is for translating the rotary movement of the spindle into a rectilinear movement of the draft connection, so as to enable the body manufacturer to install the handle *n* in the position as shown in Figs. 1 and 2, close to the edge of the door which permits the operator to more easily actuate the control by pushing on the handle instead of pulling.

The lever is provided at the other end from which the draft member is connected with a turned up ear *o* which is adapted to be engaged by the crank shaft portion of the spindle whereupon the movement of the spindle causes a corresponding movement of the bell crank and connections therewith.

Such a reversible means in the control is adapted for use with other kinds of rotary actuators as well as the vertical spindle actuator, as shown in the drawings. It is preferable to attach the draft connections to the crank shaft and to the bolt by a detachable and lost motion connection which is more clearly described and claimed in my co-pending application, Serial No. 15,174.

What I claim is:

1. In a remote control latch for automobile bodies, the combination of a latching unit on the inside of the door and provided with a bolt retractable upon closing the door, and an actuator unit positioned on the inside of the door, remote from said latching unit, and provided with a vertical rotary spindle and connections between said two units including motion translating and reversing units.

2. In a remote control latch for automobile bodies, the combination of a latching unit positioned on the inside of the door and provided with a bolt retractable from the outside of the door, an actuator unit positioned on the inside of the door at a point remote from a latching unit to make said bolt easily retractable by the occupant of the automobile, said actuator having rotary motion only, a draft connection between said latching unit and said actuator unit and means connecting said draft connection to the actuator including a motion translating and reversing means for translating and re-

versing the rotary action of the actuator into a rectilinear motion for retracting the bolt.

3. In a remote control latch, the combination of a latching unit, an actuator unit remotely located from said latching unit and provided with an actuator plate and a rotating actuator, and connections between said latching unit and actuator unit the latter including a lever arranged to be moved by the rotating actuator to translate and reverse the rotary motion of the rotating actuator into a rectilinear motion of the sliding bolt.

4. In a remote control latch, the combination of a latching unit provided with a sliding bolt, an actuator unit remotely located from said latching unit and provided with an actuator plate, a lever pivoted thereon and a rotary actuator supported thereby, and draft connections between said lever and the remote latching unit, said lever arranged for translating and reversing the rotary motion of said rotary actuator into a rectilinear motion of said latch bolt where- 25 by the bolt is withdrawn upon operating the said actuator.

5. In a remote control latch, for automobile doors, the combination of a latching unit provided with a sliding bolt, an actuator unit having a vertical rotary spindle journaled thereon and extending up through the garnish moulding and having a rotary motion only and connections between the sliding bolt carried by the latch and the vertical rotary spindle for translating and reversing the motion developed in the rotary spindle into a rectilinear motion for operating the sliding bolt.

6. In a remote control latch, the combina-

tion of a latching unit, an actuator unit 40 which includes an actuator plate, a rotary actuator supported thereby, a lever pivotally supported on said plate, connections between the latching unit and the lever supported in said actuator unit, said lever formed with an ear which permits the rotary actuator of the actuating unit to engage said ear for the purpose of imparting motion to said lever for translating and reversing the rotary motion of the actuator into a rectilinear 50 motion of the latch units.

7. In a remote control latch, the combination of a latching unit provided with a sliding bolt, an actuator unit comprising an actuator plate a vertical rotary spindle journaled thereon and a lever pivoted thereon, and a draft member for connecting the lever to the sliding bolt whereby motion imparted to said lever is reversed and translated into a rectilinear motion of the sliding bolt, said 60 draft connection provided with means which permits a quickly detachable and lost motion connection between the draft member, lever and latching unit.

8. In a remote control latch for automobile bodies, the combination of a latching unit, an actuator unit, positioned remote from said latching unit, said actuator unit including a vertical spindle actuator and a lever pivoted to the actuator plate, and a 70 draft connection between said pivoted lever and the bolt of said remote latch unit whereby the rotary motion of the vertical spindle will be reversed and translated into a rectilinear motion for retracting the bolt.

In testimony whereof I have affixed my signature.

ERNEST E. HEINTZ.
